UNITED STATES PATENT OFFICE.

FRANK ROGERS, OF NEW YORK, N. Y.

CAN-CAPPING MACHINE.

SPECIFICATION forming part of Letters Patent No. 757,842, dated April 19, 1904.

Application filed October 1, 1902. Serial No. 125,457. (No model.)

To all whom it may concern:

Be it known that I, FRANK ROGERS, a citizen of the United States, and a resident of the city of New York, borough of Manhattan, in the county and State of New York, have invented new and useful Improvements in Can-Capping Machines, of which the following is a full, clear, and exact description.

My invention relates to improvements in can-capping machines, the same being especially capable of use in uniting the caps to metallic cans without the use of solder, and by bending the cap in a way to form an interlocking seam which hermetically closes or seals the can, so as to preserve the contents thereof against deterioration under atmospheric changes.

One object that I have in view is the provision of a simple and compact machine, in which a crimping-head and a work-holder are automatically and positively driven in a manner to continuously carry on the operations of moving the cans and caps to the head, bending or crimping these parts so as to unite them, and finally move the completed article away from the head.

A further object that I have in view is to provide an improved construction of the crimping-head, which is rotarily driven in a way to positively rotate the successively active mandrels that first bend the work to a certain condition and thereafter complete the bending operation in order to secure the interlocking of the cap and the can-head, such successive operations of the mandrels and their return to normal position being effected automatically by mechanism timed to work in unison with the motion of the work-holder.

A further object that I have in view is the provision of means to automatically impart a reciprocating motion to the work-holder in order that the latter may be moved at proper intervals away from the crimping-head for the purpose of enabling the operator to replace the completed can and replace it by a can and its cap, after which the actuating devices operate to again move the holder and the work into operative position relative to the crimping-head.

50 Further objects and advantages of the in-

vention will appear in the course of the subjoined description, and the novelty will be defined by the annexed claims.

Reference is to be had to the accompanying drawings, forming a part of this specification, 55 in which similar characters of reference indicate corresponding parts in all the figures.

Figure 1 is a sectional elevation of a can-capping machine constructed in accordance with my invention. Fig. 2 is a diagrammatic detail view, on an enlarged scale, embracing the spindle-foot and mandrels in normal position and the movable bearings, levers, links, sleeve and latter's connected and actuating link, lever, rod, and cam, an end elevation of 65 said cam as connected being shown and also to the left of it a front outline thereof and its trundle-roller. Also immediately below the spindle-foot and mandrels and on a corresponding scale is shown a diagrammatic view 70 of a can-lid and part of a can-top in position to be acted upon by the spindle-foot and mandrels when depressed; also, immediately below and on a still larger scale a similar view of part of the said can-lid and top. Fig. 3 is a 75 diagrammatic view of the same details illustrated in Fig. 2, showing the relative location of the parts at a subsequent stage of the operation of my machine. Fig. 4 is a similar view at a still later stage of said operation. 80 Fig. 5 is a horizontal section through the crimping-head in a plane above the gearing by which the mandrels are rotated.

The operating parts of my improved machine are or may be mounted on a framework 85 of any suitable character, the same being indicated at A in Fig. 1. From this framework rises a post or standard B, having a cross-head b, and at one end this cross-head is provided with a bearing b', that is disposed in 90 vertical alinement with a bearing c at the top of the frame. These bearings accommodate a vertical counter-shaft C, which is provided with a bevel-gear c' and two pulleys c² c³, the smaller pulley c² being located below the gear 95 c'. Said gear meshes with a bevel-gear d, which is made fast with a short drive-shaft D, which is journaled in suitable bearings d', which are secured to the top of the frame, said shaft being equipped with a belt-pulley d², 100

around which is adapted to pass a belt, (not shown,) said belt adapted to be driven from a line-shaft or other source of power. In the other end of the cross-head *b* is rigidly secured 5 the upper part of a vertical spindle *E*, said spindle having a threaded upper extremity, which passes through a suitable opening in the cross-head and is adapted to receive the nuts *e* by which the spindle is rigidly secured in a 10 vertical position alongside of the post *B* and above the top of the frame. This spindle de- pends for a suitable distance below the cross- head, and at its lower end the spindle is pro- vided with a foot *F*, the latter having a flange 15 *f* at the lower part thereof. The spindle passes at a point intermediate of its length through a horizontal arm *e'*, which projects outwardly 20 from the post *B* and assists in holding the spindle steadily in place above the frame. 25 *G* designates a rotary crimping-head, which is loosely mounted on the spindle at a point between the foot *F* and the arm *e'*. This ro- tary head consists of a pulley *g'*, journaled upon the spindle *E*, from the bottom of which 30 pulley projects a concentric downwardly-dis- posed shell or casing *g*, rigidly secured thereto and having a rigid bottom or floor likewise journaled upon *E*, which floor bears upon foot *F*, whereby said head is rotatably supported 35 upon spindle *E*, said pulley being provided with slots or openings suitably shaped for the accommodation of the levers, and said floor with slots or openings for the accommodation of the mandrels, hereinafter described. The 40 head *G* is supported on the spindle in a position to bring the pulley *g'* in the same hori- zontal plane as the pulley *c'* on the vertical counter-shaft *C*, and these pulleys *c' g'* are opera- tively connected by an endless belt *C'*, 45 whereby the head is positively driven by di- rect gear connections with the counter-shaft. The rotary head carries mandrels adapted 50 to bend or crimp the cap into interlocking en- gagement with the can-head, and I preferably 55 equip the head with two mandrels *H I*, al- though the number of mandrels is not mate- rial. These mandrels are mounted in the head 60 on opposite sides of the spindle *E*, which passes through the head and on which it is 65 mounted and the lower ends of said mandrels project below the head. The mandrel *H* is 70 equipped with a former *h*, having a reduced and beveled lower end *h'*, and this former is 75 adapted to preliminarily bend the edge of the 80 can-cap from the condition shown in Fig. 2 to a condition illustrated by Fig. 3. The other man- 85 drel *I* is provided at its lower protruding end with a former *i*, having an enlarged and be- 90 veled lower extremity *i'*, and this mandrel and 95 its former are adapted to operate on the work 100 subsequently to the former *h* on the mandrel *H*, whereby the former *i* is adapted to com- 105 plete the work begun by the former *h* and to 110 change the work from the condition shown in 115

Fig. 3 to the complete condition represented 120 by Fig. 4.

The mandrels *H I* are journaled in movable 125 bearings *J J'*, a pair of these bearings being 130 provided to receive each mandrel. The upper bearing *J* of each pair is loosely fitted in a 135 guideway *j*, which is provided on the inside 140 of the shell *g*, forming a part of the head, 145 while the lower bearing *J'* is similarly mount- 150 ed in the guideway *j'* near the lower end of 155 the shell *g*. 160

The mandrels are adapted to be positively 165 driven on the rotation of the head *G*, and this 170 end is secured by providing a gear-wheel *k* on 175 the spindle *E* and by attaching gear-pinions 180 *k' k''* to the mandrels *H I*, said gear-pinions of 185 the mandrels having intermeshing engage- 190 ment with the stationary gear-wheel *k*, which 195 is fixed on the vertical spindle *E*, as shown 200 more clearly by Fig. 5. On the rotation of 205 the head *G* the mandrels *H I* are carried 210 therewith around the spindle *E* and the gears 215 *k' k''* travel around the stationary gear *k* in a 220 manner to impart rapid rotary motion to the 225 mandrels *H I* on their axes, whereby said man- 230 drels are carried by the head in its rotation 235 and they are driven simultaneously on their 240 axes in a positive manner. 245

The rotary head *G* also carries means for 250 alternately bringing the mandrels *H I* into op- 255 erative position relatively to the work. In 260 one embodiment of this mandrel-adjusting 265 mechanism I employ the levers *L L'*, which 270 extend through the head *G* outside of the 275 mandrels, each lever being fulcrumed at a 280 point intermediate of its length, as by secur- 285 ing it to one of the slideable bearings *J* by 290 pivot *l* and the lower end of said lever being 295 disposed so as to contact and press inwardly 300 against the outwardly-disposed end of one of 305 the slideable bearings *J'*, to which it may be 310 also connected, if desired, in any convenient 315 manner, as by a pivotal connection similar to 320 that securing it to bearing *J* in order to insure 325 that such lever may positively move said bear- 330 ing not only inwardly but also outwardly. 335 The upper ends of the levers terminate within 340 the space of the pulley *g'*, and to the lever *L* is 345 pivoted one end of a link *m*, while to the other 350 lever *L'* is pivoted one end of a link *m'*, the lat- 355 ter having a certain amount of lost motion at 360 its pivotal connection with said lever *L'*. The 365 inner ends of the links *m m'* are pivoted to a 370 sleeve *M*, which is slideable vertically on the 375 spindle *E* and is arranged below the guide- 380 arm *e'*. The links *m m'* are not connected to 385 the sleeve at the same height, and I attach 390 importance to having one pivoted to the sleeve 395 at a point below the pivotal connection of the 400 other link thereto. In the example shown by 405 the drawings the link *m* is pivoted to the 410 sleeve at a point near the lower end thereof, 415 while the other link *m'* is pivoted to said 420 sleeve near the upper end thereof, and this 425

arrangement is important, because the two links serve to bring the mandrels H and I into the positions for service dissimultaneously. The sleeve is provided with a collar o, which is attached loosely thereto, and to this collar is pivoted the lower end of a link o', the upper end of which is pivoted to a lever O, the latter being hung on the post B. To the other end of this sleeve-adjusting lever O is pivoted a driving-rod O², arranged in a vertical position between the shaft C and the post B. The lower end of this driving-rod is provided with a trundle-roller p, arranged to ride upon the periphery of the cam P, the latter being secured firmly to a cam-shaft P', the shape of said cam P being indicated in Figs. 2 and 4, inclusive. This cam is provided with a high part p², a low part p³, and an intermediate part p⁴. The cam-shaft P' is journaled at one end in a suitable bearing-frame, while the other end of said shaft is supported in a bearing at the lower end of a hanger P², which is fastened to the top of the frame. This cam-shaft P' is provided with a large bevel-gear Q, which has engagement with a bevel-gear pinion q on a vertical shaft Q', the latter being journaled in suitable bearings at the upper part of the machine-frame. This shaft Q' is provided with a pulley q', arranged in the same horizontal plane as the pulley c², and a belt Q² connects these pulleys q' c², so as to drive the shaft P' from the shaft C through the train of gearing.

R. designates the work-holder, which is arranged immediately below the rotary head and the crimping devices carried thereby, said holder adapted to present the work in operative relation to the formers h i and to hold the work in a stationary position during the rotation of the head and the crimping devices.

This holder is rigidly attached to the upper end of a stem S, which is mounted for reciprocating movement in suitable guides r r' on the framework, and this stem is held against turning by a set-screw s, attached to the guide r' and arranged to work in a slot or groove s' at the lower part of the stem. The stem and the holder are normally pressed in a downward direction by springs T, arranged to act on a collar t, which is secured to the stem S at a point between the guides r r', said springs bearing against a plate t', fitted to the under side of the guide r.

The stem and the holder are designed to be positively and automatically lifted at suitable intervals and to be held in a raised position during the period that the formers are rotating with the head in order to crimp the cap at the can-head, after which the stem and the holder are lowered. Any suitable means may be provided for intermittently and automatically actuating the stem and the holder; but the simplest means which I contemplate using resides in a cam U, which is secured to one end of the cam-shaft P' and is arranged to pe-

ripherally ride against the lower end of the stem S, or a trundle-roller, as S', may be employed on this stem to ride against the periphery of the cam similar to the roller p of the driving-rod O².

The operation is as follows: Assuming that the parts are properly driven and that the cam U is in a position to permit the holder and the stem to be lowered by the pressure of the springs T, the operator places a can and its cap on the holder R, immediately after which the cam U becomes effective to raise the stem and the holder, and thereby move the can-head and the cap into position for engagement by the parts of the rotary head. On the elevation of the can and its cap the foot F enters the recess in the cap, said cap being indicated at 5 and the can-head at 6. The can and the cap are clamped by and between the holder R and the foot F on the spindle, and this foot presents its beveled end f quite close to the upstanding flange 7 of the cap 5, so as to afford a backing therefor. The work having been properly lifted and clamped, the trundle-roller p passes from the low part p³ of the cam P to the intermediate part p⁴, and the rod O² and the lever O are thereby moved for limited distances, so as to lower the sleeve M from the position shown by Fig. 2 to the position shown by Fig. 3. During this movement the link m is drawn to a horizontal position and the lever L is shifted so its lower end will press the bearing J' toward the spindle E and the foot F, whereby the former h on the mandrel H will be brought into engagement with the flange 8 of the cap, and the rotation of the head G and the action of the former h will bend this flange 8 from the condition shown by Fig. 2 to the inclined condition shown by Fig. 3. The continued rotation of the cam P moves the trundle-roller upon the high part p², and the sleeve M is now fully depressed, so as to make the link m' take the horizontal position shown by Fig. 4, while the link m is moved to an inclined position. This shifting adjustment of the links m m' withdraws the mandrel H and the former h away from the flanged cap, while the other lever, L', is moved to force the other bearing, J', inwardly, and thereby bring the former i on the mandrel I into position for engagement with the bent flange, (shown by Fig. 3,) so that the former i on the rotation of the head and of the mandrel will bend this flange to its complete condition, as shown by Fig. 4. The roller p now enters the low part p³ of the cam P, and the mandrels and the sleeve are returned to their normal positions. In the meantime the cam U allows the springs T to force the collar t, the stem S, and the holder R downwardly to withdraw the capped can from the rotary head, thus allowing the operator to remove the complete can and replace it by another can and its cap.

It will be observed that the two mandrels

and their formers are rotated constantly on their axes and that they rotate with the head G around the axis afforded by the spindle E; but the levers L L' are so controlled by the sleeve M, the links, and the cam P that the mandrels and their formers are brought successively into position for engagement with the flanged can-cap, whereby the former h preliminarily bends the cap-flange to an inclined position, and the former i thereafter completes the bending of the cap-flange, so as to unite the cap to the can-head by an interlocking joint, which hermetically seals the can without the use of solder.

15 I am aware that can-capping machines have been previously constructed comprising a combination of a work-holder, a rotary head, crimping devices mounted in said head to rotate therewith, and to which crimping devices rotation on their axes has been imparted by pressure upon their working edges due to the contact of the latter with the can or cap, and I do not wish to be understood as broadly claiming any such device, my own invention being distinguishable therefrom by reason of my imparting to my crimping devices by appropriate means a positive rotation upon their axes, which rotation is independent of any pressure applied on their working edges, in consequence of which my crimping devices are prevented from jamming under abnormal conditions, a tighter and more perfect seam effected between can and lid, and risk of breakage and other injury diminished.

Having thus described my invention, I claim as new and desire to secure by Letters Patent—

1. In a can-capping machine, the combination of a rotary head, means for presenting work to said head, mandrels mounted in said head to rotate therewith and each capable of rotation on its axis, means for rotating said mandrels on their axes simultaneously with the rotation of the head, and automatic devices for successively moving said mandrels in active relation to the work.

2. In a can-capping machine, the combination of a rotary head, means for presenting work to said head, rotary mandrels mounted in said head to turn therewith and each provided with a former, means for rotating the mandrels on their axes, and means for alternately adjusting said mandrels to bring the formers thereof successively into engagement with the work.

3. In a can-capping machine, the combination of a fixed spindle, a clamping-foot attached thereto, a reciprocating stem in line with said spindle, a work-holder mounted on said stem and disposed in opposing relation to the clamping-foot, a retractor operable to move the stem and the holder away from the foot, a cam arranged to positively move the stem and the holder toward the foot, and

crimping-formers revoluble around the clamp-foot.

4. In a can-capping machine, the combination of a spindle, a rotary head mounted on said spindle, mandrels carried by said head and geared to the spindle for rotation on their axes simultaneously with the rotation of the head, formers carried by the mandrels, means for presenting work to said formers, and means for adjusting the mandrels and the formers successively in position for engagement with the work.

5. In a can-capping machine, the combination of a rotary head, mandrels provided with formers and mounted in said head to rotate therewith, means for turning the mandrels on their axes, a suitable collar, and connections between said collar and the mandrels to successively adjust the formers into positions for action on the work.

6. In a can-capping machine, the combination of a rotary head, mandrels carried by said head, and having means for rotating them on their axes, levers mounted on the head and operatively related to the mandrels for adjusting them, a slidable collar linked to said levers, and a cam arranged to impart slidable movement to said collar.

7. In a can-capping machine, the combination of a spindle, a rotary head mounted thereon, a clamping-foot carried by the spindle, mandrels mounted in the head to rotate therewith and geared to said spindle for rotation on their axes, a collar slidable on the spindle, levers mounted in the head and operatively arranged to the mandrels, links connected to the levers and pivoted at different points to the collar, a cam, and connections between said cam and the collar to impart a progressive slidable movement to the latter.

8. In a can-capping machine, the combination with a work-holder, of a rotary head, crimping devices mounted in said head to rotate therewith, and means for positively rotating said crimping devices on their axes, simultaneously with the rotation of said head, and independently of pressure applied to their working edges.

9. In a can-capping machine, the combination of a non-revoluble work-holder, means for imparting slidable movement to said work-holder, a rotary head occupying an operating relation to said work-holder, crimping devices mounted in said head to rotate therewith, and means for positively rotating the crimping devices on their axes and independently of pressure applied to their working edges.

In testimony whereof I have signed my name to this specification in the presence of two subscribing witnesses.

FRANK ROGERS.
